Filed Aug. 10, 1970, Ser. No. 24,401

Term of patent 14 years

Int. Cl. D6—01

U.S. Cl. D6—198

FIG. 1 is a front elevational view of a headboard for a bedstead or similar article, showing my new design; and FIG. 2 is a fragmentary cross-sectional view taken on lines 2—2 in FIG. 1.

The back, not shown, is substantially flat and unornamented.

Portions of FIG. 1 are lined to indicate contrast in appearance.

I claim:

The ornamental design for a headboard for a bedstead or similar article, as shown and described.
